UNITED STATES PATENT OFFICE.

MELVILLE C. BARNARD, OF WINTHROP, MASSACHUSETTS.

DESIGN FOR A BADGE OR SIMILAR ORNAMENT.

47,128.

Specification for Design.

Patented Mar. 23, 1915.

Application filed December 14, 1914. Serial No. 877,250. Term of patent 7 years.

To all whom it may concern:

Be it known that I, MELVILLE C. BARNARD, a citizen of the United States, residing at Winthrop, in the county of Suffolk and State of Massachusetts, have invented a new, original, and ornamental Design for a Badge or Similar Ornament, of which the following is a specification, reference being had to the accompanying drawings, forming part thereof, and in which

I claim:

The ornamental design for a badge or similar ornament, as shown.

MELVILLE C. BARNARD.

Witnesses:

JOHN A. WHELAN,
B. JOFFE.
